Specification for Design.

Patented Aug. 21, 1917.

Application filed July 2, 1917. Serial No. 178,261. Term of patent 3½ years.

To all whom it may concern:

Be it known that I, IRVING R. LEDERER, a citizen of the United States, residing at Providence, in the county of Providence and State of Rhode Island, have invented a certain new, original, and ornamental Design for a Protector for Articles to be Worn on the Wrist, of which the following is a specification.

In the accompanying drawings which

form a part of this specification Figures 1 and 2 are a plan and edge view respectively of a protector for use with wristlet watches and similar articles to be worn on the wrist and showing my new design.

I claim:

The ornamental design for a protector for articles to be worn on the wrist, as shown.

IRVING R. LEDERER.
